William S. Fowler
ATTORNEY

UNITED STATES PATENT OFFICE.

HARRY FLOYD STILLSON, OF WILLIAMSBURGH, ONTARIO, CANADA.

TELEPHONE ATTACHMENT.

Application filed March 23, 1923, Serial No. 627,242. Renewed March 30, 1925.

To all whom it may concern:

Be it known that I, HARRY FLOYD STILLSON, a citizen of Dominion of Canada, and resident of Williamsburgh, in the county of 5 Dundas and Province of Ontario, Dominion of Canada, have invented certain new and useful Improvements in Telephone Attachments, of which the following is a specification.

10 This invention has relation to certain new and useful improvements in telephone construction, and has for its primary object the provision of an attachment which may be readily substituted on certain types of 15 telephones for the ordinary crank employed at the present time for ringing up other parties included in the system.

Another object of the invention resides in the provision of a telephone attachment 20 of the character stated, which will be of simple construction and operation as well as highly efficient in use, and which may be operated by simply forcing inwardly the operating rod projecting from the telephone 25 box or casing.

Another object of the invention resides in the provision of a telephone attachment of the character stated in which the operating rod will have a longitudinal movement for 30 limited distances to cause rotary movement of the rotatable shaft operating the ringing or calling up mechanism within the telephone box or casing, such operation being caused as the operating rod is moved longitudinally in one direction without rotation of the operating rod; the operating rod being permitted free rotation when returning 35 to normal position without affecting the rotatable shaft.

40 The invention has for a further object the provision of a telephone attachment of the character stated which will be constructed in such a manner that either a long ring or a short ring may be correctly given, as desired.

45 A still further object of the invention resides in the provision of a telephone attachment of the character stated which will be composed of the minimum number of parts 50 of simple construction and arrangement and in which the distance of movement of the operating rod will be limited according to the distance to which it is turned previous to operation, thereby determining the length

of the ring given to the other party on the 55 line.

With the foregoing and other objects in view as will appear as the description proceeds, the invention consists in the novel construction, combination and arrangement of 60 co-operating elements as hereinafter more specifically set forth, claimed and shown in the accompanying drawings forming a part of the present application, in which:

Fig. 1 is an elevation of the attachment 65 in use, a portion of the telephone box or casing being included in this view.

Fig. 2 is an elevation at right angles to Fig. 1.

Fig. 3 is a vertical section substantially 70 on the plane of line 3—3 of Fig. 1, looking in the direction indicated by the arrows.

Fig. 4 is a transverse section substantially 75 on the plane of line 4—4 of Fig. 3, looking in the direction indicated by the arrows.

Fig. 5 is a detailed section substantially 75 on the plane of line 5—5 of Fig. 2, looking in the direction indicated by the arrows.

Fig. 6 is an enlarged detailed section substantially 80 on the plane of line 6—6 of Fig. 3, looking in the direction indicated by the arrows.

Referring more in detail to the drawings in which similar reference characters designate corresponding parts throughout the 85 several views it will be noted that an operating rod 10 is substituted for the crank usually employed on the telephone included in the systems which provide for each party ringing up or calling the other party desired in 90 the same system.

As shown clearly in Figs. 2, 3 and 4, the operating rod 10 has spiral threads 11 arranged thereon and working in spiral grooves 12 formed in a sleeve 13 which has a solid inner end threaded in the coupling sleeve 14 which also receives the threaded end 15 of the rotatable shaft 16 forming a part of the ringing or calling up mechanism within the telephone box or casing 17. It is 100 to be noted that the coupling sleeve 14 and the sleeve 13 take the place of the crank or handle heretofore employed. It will also be apparent by referring to Fig. 3, that the sleeve 13 extends through the opening 18 in the telephone box or casing 17 from which the crank or handle has been removed. An annular flange 19 is extended radially from

the outer end of the sleeve 13 and serves as a bearing member having continuous ball races 20 in its under face to receive the bearing balls 21 positioned between the flange 19 and the out-turned flange 22 of the supporting and sleeve enclosing member 23. This member 23 is in the form of a tube extending into the opening 18 of the telephone box or casing 17. A bearing enclosing cap 24 is engaged over the flange 19 and threaded or otherwise secured onto the flange 22, as shown clearly in Fig. 3. It will also be seen from this view that the cap 24 has a central opening 25 through which the operating rod 10 works, as will be later clearly understood.

In order to secure the member 23 in position, an annular flange or plate 26 is formed thereon and secured to the outer face of the telephone box or casing 17 by suitable securing members 27. An arm 28 is extended from the flange or plate 26 and parallel with the oscillating rod 10. A pair of comparatively long and comparatively short slots 29 and 30, respectively, are extended longitudinally in the outer portion of the arm 28 and connected at their outer ends by the cross slot 31, as shown in Fig. 5. The purpose of the slots 29, 30 and 31 will presently appear.

The operating rod 10 has a head 32 mounted on its outer end with a finger 33 extended laterally therefrom and working in the slots 29, 30 and 31 of the arm 28. A ratchet wheel 34 is mounted on the end of the operating rod 10, within the head 32 and has engaged therewith the pawl 35 which is pivotally mounted in the head 32 and resiliently retained in operative position. It will, therefore, be seen that the operating rod 10 will be retained against rotation when forced inwardly, so as to compel rotation of the sleeve 13, the coupling sleeve 14 and the rotatable shaft 16 operating the ringing or calling up mechanism within the telephone box or casing 17. The operating rod 10 will be permitted to rotate freely as it is returned to its outermost or normal position. A helical spring 36 is extended around the outer portion of the operating rod 10 with one end of the spring 36 bearing against the outer face of the bearing cap 24 while its other end bears against the collar 37 extended around the operating rod 10 and secured on the end of the head 32 to prevent the operating rod 10 from working out of said head 32. The spring 36 serves to return the operating rod 10 and also the head 32 to normal or unoperated position after each operation and resiliently retain these parts against movement with the finger 33 located in the cross slot 31, as shown in Figs. 1, 3 and 5.

It is believed the complete construction and operation may now be apparent from

the foregoing paragraphs taken in connection with the accompanying drawings without further detailed description. It may be briefly stated, however, that when it is desired to give a long ring, the head 32 is turned to bring the finger 33 opposite the long slot 29 and the head 32 is then pressed in, forcing the operating rod 10 inwardly to compel rotation of the sleeve 13 and the parts connected therewith, thus giving a long ring of the ringing or calling-up mechanism of the telephone. As soon as the head 32 and operating rod 10 have been forced in and released, the spring 36 will serve to ordinarily return them to normal position. If a short ring is to be given, the head 32 must be turned in the opposite direction to present the finger 33 to the end of the short slot 30 of the arm 28. Then, by forcing in the head 32 and operating rod 10 and releasing them, a short ring will be given and the released operative parts of the attachment returned to their normal positions. It is to be understood that either the long ring or the short ring may be repeated any number of times desired and owing to the construction and operation of the parts of the device, these rings of uniform length or duration are issued. It is also to be understood that the complete device may be readily substituted for the crank employed on rural telephones and the like without any alteration in the arrangement and operation of the parts of the telephone.

While the preferred embodiment of the invention has been disclosed, it is to be understood that minor changes in the details of construction, combination and arrangement of co-operating elements may be resorted to within the scope of what is claimed without departing from the spirit of the invention.

What I claim as new is:

An attachment for a telephone including the combination with the telephone box and the rotatable shaft of the calling up mechanism; of a member mounted on said telephone box and extended into the same opposite the rotatable shaft; a guide arm carried by said member and provided with connected long and short slots; a sleeve operable within said member and having a bearing disc; said sleeve having spiral grooves therein; the first mentioned member having a bearing disc opposite to the first mentioned bearing disc; bearing balls operable between said discs; a cap for said discs; an operating rod having threads working in said grooves to rotate said sleeves and the rotatable shaft of the calling up mechanism when the operating shaft is moved in one direction within the sleeve; a head for said operating rod; means within said head for preventing rotation of said operating rod when moved longitudinally to rotate said

sleeve; means for resiliently retaining said head and said operating rod in extended unoperated position; and a guide finger extended from said head and working in said 5 slots of the guide arm for guiding said head and said operating rod and limiting movement thereof to determine the length of the

ring given by operation of the rotatable shaft of the calling up mechanism and the sleeve connected to said rotatable shaft. 10

In testimony whereof, I affix my signature.

HARRY FLOYD STILLSON.
